ELECTRON DISCHARGE TUBE

Gunther Jobst and Franz Sammer, Berlin, Germany, assignors to Telefunken Gesellschaft für Drahtlose Telegraphie m. b. H., Berlin, Germany, a corporation of Germany

Application May 16, 1934, Serial No. 725,838
In Germany May 17, 1933

1 Claim. (Cl. 250—27.5)

The present invention is concerned with a discharge tube and more particularly to means for shielding the discharge paths thereof by the aid of one or more metallic envelopes or enclosures which do not contain insulating parts and means maintained at indefinite potentials. It is obvious that discharge paths in electron tubes, which are known as the most sensitive relay system available at the present time, will respond even to the feeblest disturbances, the sources of which may be both outside as well as inside the discharge vessel, so that the most careful shielding of the tubes and more particularly of the discharge paths thereof is desirable. This consideration is especially important in the input stages of an amplifier or receiver, for it is here where small useful or working amplitudes are involved whose level might fall below the stray or disturbance level or might be influenced by the latter. In line with these conceptions a number of protective ways and means have been suggested in the earlier art with a view to either rendering stray fields coming in from the outside harmless or else to exclude the influence of charges that have accumulated on the tube wall. Among these may be mentioned the metallization of the glass bulb upon the inner or outer surfaces, the disposition of a metallic cylinder between the glass wall and the electrode system, or else the encasing of the electrode system inside a metallic box-like structure. However, it has been found that the said protective steps are not invariably adequate; in fact, they prove particularly deficient in the attempt to preclude the disturbances which are occasioned by such electrons as stray away from the discharge path proper and the action of stray fields upon the electrons. In order that this may be accomplished to the greatest possible degree it is, on the contrary, necessary according to the present invention not only to surround the electrode system all around by a metallic sheath in a way resembling a Faraday-cage arrangement from which only such means as are required for the supporting of the electrodes and for the supplying or lead-in of the current are projected, but in addition, care must be taken that no insulating parts will be contained inside such a cage.

For a better understanding of the basic idea of the invention, reference may here be made to the following relations and phenomena inside a discharge tube: Every electrode system of the form of construction heretofore known offers a chance for electrons drifting or flying away at different points along the path of the discharge

proper between the cathode and the anode and to move elsewhere through the glass bulb. Such points where straying away of electrons occurs, are located at the open ends, for instance, in electrode systems having electrodes open at both ends and being of cylindrical or prismatic form. Electrons will also fly off or drift in the space surrounding the electrodes whenever the outermost electrode, which serves as the anode and which is maintained at a high positive potential, is apertured or formed of wire gauze material. This type of anode electrode has been adopted for thermal reasons with a view to promoting rapid heat conduction or radiation from the interior of the discharge space and to precluding undesirable temperature rises conducive to thermal emission of unheated electrodes, as for example, the grid. The escape of electrons from the discharge path proper is also favored particularly in the case of electrode systems of the kind in which the outer electrode constitutes no closed surface as is frequently true with plate-shaped anodes. The disturbances which are liable to be caused by electrons in the vacuous space as stated may be of widely different nature, and they depend both upon the action of outside fields as well as the electrical state of insulation parts.

Electrons located between the electrode system and the glass wall are causative of space charges, the existence and distribution of which is frequently a function of uncontrollable factors. They are therefore often quite unstable, indeed, they evidence inclination to experience sudden changes which manifest themselves, for instance, in the form of crackling noises or hisses. Under certain circumstances there may occur periodic oscillatory movements of these free space charges in the way as observed in the case of Barkhausen-Kurz oscillations. At any rate, it can be readily understood that these space-charges are considerably more responsive to outside fields than the stream of electrons passing inside the discharge space proper between the electrodes and controlled by definite potentials.

Other disturbances may originate from insulators or metal parts mounted inside the glass bulb, which parts are maintained at definite potentials and are charged up by electrons. The size and the existence or duration of these charges depends often upon accidental factors, and this introduces a further unsafe element in the function of the tube.

Finally, secondary-emission effects of the insulator parts may be emphasized. The inner wall of the glass bulb as well as the insulating

bridge means used for the supporting of the electrode system are liable to be charged by creepage currents emanating from the plate lead-in which is at a positive potential. This will 5 frequently arise whenever the plate potential is connected before the filament or cathode has attained its full state of emission, a condition occurring generally in the standard type of house current operated receiving sets. If these areas 10 or surfaces are struck by the electrons straying away from the discharge space or penetrating through the apertured plate or anode at a rate of velocity which corresponds to the potential thereof, they are caused to give off secondary 15 emission. These electron-emitting surfaces will then act like electrodes, and inasmuch as they are in capacitive coupling relationship with the control grid they will occasion increases in damping and capacity, or decreases of these quantities, 20 according to the phase of the voltage. Now, all of these phenomena are not only disturbing, fundamentally speaking, but their presence becomes troublesome especially because the factors that are concerned are uncontrollable to a large degree and are a function of accidental causes or 25 conditions.

To preclude these difficulties, it is suggested according to this invention to surround the electrode system with a shielding member which is 30 completely closed all around like a Faraday cage, care being taken to have no insulating parts, such as electrode bridges or spacers, inside the shielded or protected space and also no conductors, such as getter supports sealed directly in the squash, 35 that are not kept at a definite potential. Excepted from this limitation, of course, are non-metallized parts of the ceramic cathode tube in the case of indirectly heated cathodes; for since the same, on the one hand, are connected with 40 the cathode potential, and are, on the other hand, located outside the trajectory of the electrons, no disturbance by such areas need to be feared. But in a case of necessity it is easy to see to it that the whole part of the ceramic 45 cathode support located within the shielding enclosure is metallized or covered by distinct shielding means or surfaces. This affords an insurance that neither uncontrollable charges will be built up nor that secondary electron emission from insulator parts will occur. The shielding enclosure or envelope could be made also apertured so that the thermal properties of the electrode system so far as thermal radiation from the interior of the discharge space is concerned, will not be impaired. In order that in 55 this case the passage of electrons in the space outside the cage may be prevented, the latter may be connected to a fixed low potential, preferably negative, or to the cathode potential.

60 In the cage normally enclosing the electrode system on all sides certain portions could be

omitted at such places where no electrons are able to drift away or where no action upon the discharge process is possible. This is true, e. g., when the plate consists of an unbroken, solid sheet cylinder; in this case the shielding may be 5 insured by two caps fitted on at the end surfaces.

In the accompanying drawing which forms part of this application, Figs. 1 and 2 disclose two modifications according to the invention.

Fig. 1 shows an electrode system having a 10 shielding cage or enclosure surrounding the system on all sides. 1 is the glass bulb with the squash 2 on which the electrode system is mounted. 3 denotes the cathode, 4 a grid electrode, and 5 an anode consisting, for instance, of 15 a metallic network or gauze. The electrode system or assembly is surrounded by a cage or enclosure which consists of a cylindrical metallic network 6 and two end surfaces 7 and 8, which may be either a solid metal disc or an apertured 20 disc. The cage is provided with a lead 9 in order that it may thus be connected, if desired, to any convenient potential. The enclosure, however, could also be united inside the glass bulb with an electrode having a suitable voltage, say, for 25 instance, the cathode. The electrodes are supported and spaced apart by the aid of insulation bridges 10 and 11 which are placed outside the said enclosure or shield. Also the getter support 12 is disposed outside the cage. 30

Fig. 2 illustrates a tube whose electrode assembly comprises an anode or plate consisting of a solid-sheet cylinder 20. As a consequence it is sufficient to provide shielding electrodes only at the two end surfaces of the anode cylinder. 35 These consist of two caps 21 and 22 made from metal gauze which are fitted on so as to engage so far over the ends of the electrode system that the escape of electrons into the space outside the enclosing shield is practically precluded. With 40 this arrangement there is little possibility for the insulating bead 23 serving as a support for the electrode holding means being struck by electrons. 45

What is claimed is:

An electron discharge device comprising cathode, grid and anode electrodes, a shield member surrounding the anode electrode and having portions extending beyond the opposite ends of said anode electrode, a shield disc at each end of 50 the shield member and joined thereto to completely enclose the electrodes contained therein, parallel support rods for said grid and anode electrodes and said shield member extending beyond the edges thereof, and insulating spacing 55 members engaging the opposite ends of said support rods beyond the shield discs, said shield member and said shield discs being formed of wire mesh material.
